DOOR CONTROLLED LIGHTING UNIT

Vincent F. Geraci, Cleveland, Ohio

Application May 13, 1952, Serial No. 287,480

1 Claim. (Cl. 240—2)

1

This invention relates to door controlled lighting units of the kind intended for use in supplying illumination to the interior of a closet, cabinet or other enclosure and as one of its objects provides a lighting unit of this kind which is of a very simple, practical and economical construction and which is in the form of a complete self-contained device which can be quickly and easily installed merely by mounting the same on the door frame.

Another object of the invention is to provide a lighting unit of the character mentioned having novel lever means for transmitting movement to a projecting switch actuating plunger such that the unit can be disposed at a location in the closet or enclosure which will afford more satisfactory illumination with minimum obstruction of the door opening.

A further object is to provide a lighting unit of the kind referred to above in which the lever means comprises a bell crank lever pivoted for relative swinging for engagement of one arm thereof with the switch plunger and a thrust element carried by the other arm of the bell crank lever and adapted to be engaged by the door.

Still another object is to provide a lighting unit of the type above indicated comprising a cover-attached mounting bracket and a tubular sheet metal housing member having a lamp socket mounted in one end thereof and which housing member and lamp socket are connected with the mounting bracket by engagement of the other end of the housing member with the cover so as to define a switch enclosure and wherein a switch device, located in such switch enclosure, includes a movable actuating plunger extending through the cover in the general direction of the axis of the housing member.

The invention can be further briefly summarized as consisting in certain novel combinations and arrangements of parts hereinafter described and particularly set out in the claim hereof.

In the accompanying sheet of drawings:

Fig. 1 is a vertical sectional view taken through a door frame to which the novel lighting unit of the present invention has been applied, the lighting unit itself being shown in elevation;

Fig. 2 is mainly a bottom plan view of the lighting unit when viewed in the direction indicated by the section line 2—2 of Fig. 1; and

Fig. 3 is a vertical section taken through the lighting unit and an adjacent fragmentary portion of the door frame, as indicated by section line 3—3 of Fig. 2.

2

As one practical embodiment of the invention, the drawings show the novel lighting unit 10 mounted on a door frame 11 so as to be located in a closet space or enclosure 12 and inwardly of the door opening 13 leading into such space or enclosure.

The door opening 13 is defined by the door frame 11, which is located in the upright building wall 14. The door frame 11 is of a conventional form comprising upright and transverse jamb members 15 and 16 and a pair of front and rear casing members 17 and 18. The door opening 13 is controlled by an outwardly swinging door 19 of a conventional form, which in its closed position engages a stop strip or batten 20 of the door frame 11, as shown in Fig. 1.

The lighting unit 10 includes a housing 22 having a lamp socket 23 mounted therein at one upper end thereof, and a switch device 24 located in the housing and having an actuating plunger 25 projecting from the lower end thereof. The lighting unit 10 also includes a mounting bracket 26 having an angular portion 26^a adapted to be secured to the inner casing member 18 of the door frame, as by means of the screws 27, and a lateral shelf portion 26^b to which the lower end of the housing 22 is secured in the manner explained hereinafter.

The housing 22 comprises a tubular sheet metal member 28, in this instance a substantially cylindrical member, having an open lower end 28^a and at its upper end having a transverse end wall 28^b provided with an opening in which the lamp socket 23 is mounted. The lamp socket 23 is of a conventional form comprising a base 29 made of insulating material and embodying an internally threaded metal socket member 30 which extends upwardly through the end wall 28^b in insulated relation thereto and is adapted to receive the externally threaded base 31 of an incandescent lamp 32. The lamp socket 23 also comprises a clamping ring 33 made of insulating material. As shown in Fig. 3, the lamp socket is mounted in the housing 22 by the clamping engagement of the base 29 and the ring 33 with opposite sides of the transverse end wall 28^b of the housing member 28.

The housing 22 is also formed, in part, by a substantially cup-shaped cover member 34 which forms the transverse bottom wall of the housing and cooperates with the housing member 28 in defining a chamber or enclosure 35 in which the switch device 24 is located. The cover member 34 comprises a flat end wall 34^a which is seated against the laterally extending portion

26^b of the mounting bracket 26 and an annular skirt portion 34^b.

The fixture assembly comprising the housing member 28 and the lamp socket 23 is connected with the bracket 26 by the engagement of the open lower end 28^a of the housing member with the cover member 34. This engagement is here shown as being a telescoping engagement in which the open lower end 28^a is received within the annular skirt 34^b and is connected therewith by a frictional engagement, although, if desired, this connection can also be formed by the use of suitable welding or soldering.

From the construction just described above for the housing 22, it will be seen that this housing resembles a tin can in an inverted position and to facilitate the manufacture of the lighting unit 10 at minimum cost, the housing is preferably made from a conventional tin can of a suitable size, shape and construction as shown in the drawings. When the housing 22 is made from such a conventional tin can, the transverse end wall 28^b which supports the lamp socket 23, is formed by the bottom wall of the can. The cover member 34 is formed by the conventional cup-shaped friction cap of the can and is secured to the bracket 26 in a manner to be presently described. In addition to forming an enclosure for the switch device 24, the chamber 35 of the housing also provides a space in which the wires 36 connecting the switch device 24 and the lamp socket 23 are located and concealed.

A conductor cord 37 extends from the chamber 35 through a bushing 38 mounted in an opening of the side wall of the housing 22 and includes a terminal plug 39 adapted to be inserted into an available electrical outlet. The wires 36 are insulated from metallic contact with the side wall of the housing member 28 by a sheet of suitable insulating material 40 which forms a cylindrical inner liner in this housing member.

The switch device 24 comprises a hollow body 41 made of insulating material and having therein a pair of stationary contacts 42 and 43 and a movable contact 44 extending in bridging relation to such stationary contacts. This switch device also includes a hollow externally threaded mounting stem 45 which extends through aligned openings of the cover member 34 and the bracket portion 26^a, and the above-mentioned actuating plunger 25 which is slidable in the hollow stem 45 and is connected with the movable contact 44 by a push rod 47.

A compression spring 48 located in the hollow stem 45 and disposed between the switch housing 41 and the plunger 25, is effective on the latter to normally hold the same in a position projecting from the hollow stem, as shown in Fig. 3. The pressure of the spring 48 also acts on the plunger 25 in a direction to shift the movable contact 44 into engagement with the stationary contacts 42 and 43 whenever an outward movement of the plunger is permitted.

The threaded stem 45 of the switch device 24 also serves as a connecting means for holding the cover member 34 in connected relation with the bracket 26. For this purpose, a pair of lock nuts 49 and 50 provided on the threaded stem 45, apply a clamping force against the cover member 34 and the lateral bracket portion 26^a. In addition to the connection provided by the threaded stem 45 and the lock nuts 49 and 50, the cover member 34 can be secured to the bracket portion 26^a by suitable welding or solder-

ing if desired. When the cover member 34 is circular in plan shape as in this instance, the bracket portion 26^a has a similar circular shape as shown in Fig. 2.

Another important feature of the present invention is the provision of lever means 52 for transmitting movement to the switch actuating plunger 25 and this lever means will be described next. The lever means 52 is here shown as comprising a bell crank lever 53 and a thrust element 54 connected with such bell crank lever. A pair of laterally spaced arms 55 and 56, formed by downwardly deflected portions of the bracket 26, have laterally aligned openings in which a pair of pivot lugs 57 and 58 rotatably engage to constitute a pivotal mount for the bell crank lever 53. One of the arms of the bell crank lever 53, in this instance the arm 53^a at the fulcrumed upper end of the lever is engageable with the outer end of the switch plunger 25. The other or free arm 53^b of the bell crank lever extends in the general direction of the axis of the housing 22.

The thrust element 54 is here shown as comprising a pin carried by the free arm 53^b of the bell crank lever 53 and projecting therefrom in an angular relation such that it extends substantially normal to the axis of the housing 22 and which pin is of a length to project into the door opening 13. The thrust element 54 has an adjustable connection with the lever arm 53 and which, in this instance, is formed by a threaded portion 54^a screwed into an internally threaded opening of the lever arm and engaged by a lock nut 59.

From the construction above described for the lighting unit 10, it will be seen that this unit comprises a complete self-contained device which can be quickly and easily installed by merely attaching the bracket 26 to the casing member 18 of the door frame 11 and that when the lighting unit is installed in this manner, it will be located in the closet space or enclosure 12 in an upright position for effective illumination of such space and at a point where it will be hidden from view and will not obstruct the door opening leading into such closet space. It will also be seen that when the lighting unit 10 has been mounted in this position, the thrust element 54 of the lever means 52 will project into the door opening 13 to be engaged by the door 19 when the latter is swung to its closed position.

The engagement of the thrust element 54 by the door 19 causes swinging of the bell crank lever 53 on its pivotal mounting to thereby cause the lever arm 53^a to move the switch plunger 25 upwardly to lift the movable contact 44 and hold the same in an open position with respect to the stationary contacts 42 and 43. While the door 19 remains closed, the movable contact 44 will be retained in its open position and the supply of electric current to the incandescent lamp 32 will be interrupted. When the door 19 is opened, the thrust element 54 is released whereupon the compression spring 48 moves the plunger 25 downwardly and causes closing of the movable contact member 44 for supplying energizing current to the lamp 32.

The lighting unit 10 preferably includes the above-described lever means 52 as an important part thereof because of the advantageous mounting position which it permits for the unit and because of the increased force which will be applied thereby to the switch plunger 25, but if

desired, this lever means can be omitted and in that case, the lighting unit would be mounted on the door frame in a position such that the switch actuating plunger 25 will be engaged directly by the door 19.

Although the novel lighting unit of this invention has been illustrated and described herein to a somewhat detailed extent, it will be understood, of course, that the invention is not to be regarded as being limited correspondingly in scope, but includes all changes and modifications coming within the terms of the claim hereof.

Having thus described my invention, I claim:

A lighting unit for mounting on a door frame or the like defining a door opening and including jamb and casing members, comprising a mounting bracket adapted to be attached to a casing member of said door frame, a cover member connected with said mounting bracket, a tubular sheet metal housing member having an end opening at one end thereof, a lamp socket mounted in said housing member at said end opening, a switch supported by said cover member and comprising cooperating stationary and movable contacts, a movable plunger extending through said cover member and adapted to impart actuating movement to the movable switch contact, said housing member and lamp socket

forming an assembly which is supported by said bracket by engagement of the other end of said housing member with said cover member and said housing and cover members cooperating to define an enclosure for said switch, a bell crank lever having one arm thereof engageable with said plunger and its other arm extending in the general direction of the longitudinal axis of said housing member and being of a length to project beyond said casing member of said door frame, pivot means mounting said lever on said bracket for relative swinging, and a thrust pin carried by said other arm and projecting therefrom in angular relation to said axis and in a direction to extend transversely of said casing member and into said door opening, said thrust pin being threaded and having adjustable connection with said other arm.
